UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

CAR TRUCK.

1,410,979.

Specification of Letters Patent. Patented Mar. 28, 1922.

Application filed July 25, 1919. Serial No. 313,289.

To all whom it may concern:

Be it known that I, CHARLES T. WESTLAKE, a citizen of the United States, residing at St. Louis, Missouri, have invented a certain new and useful Improvement in Car Trucks, of which the following is a full, clear, and exact description, such as will enable others skilled in the art to which it appertains to make and use the same, reference being had to the accompanying drawings, forming part of this specification.

My invention relates to railway car trucks; the principal objects of my invention being to generally improve upon and simplify the construction of the existing types of trucks; to provide a relatively simple truck which can be easily and cheaply manufactured; and to provide means for distributing the load of the car on the journals.

With the foregoing and other objects in view, my invention consists in certain novel features of construction and arrangement of parts, hereinafter more fully described and claimed, and illustrated in the accompanying drawings, in which—

Figure 1 is a top plan view of a railway car truck of my improved construction.

Figure 2 is a side elevational view with parts broken away and in section.

Figure 3 is a transverse section taken approximately on the line 3—3 of Figure 2.

Figure 4 is a detail section taken approximately on the line 4—4 of Figure 3.

Figure 5 is a detail section taken approximately on the line 5—5 of Figure 3 and showing the bearing rollers that are interposed between the truck bolster and body bolster or car underframe.

Figure 6 is a detail section similar to Figure 5 and showing a modified form of the bearing rollers.

Figures 7 and 8 are diagrammatic views of the forms of bearing rollers used in my improved truck.

Referring by numerals to the accompanying drawings, 10, 10 designate the truck side frames, the same being preferably cast and having their ends extended as designated by 11 to form supports and points of attachment for the hangers of outside hung brake beams 12.

Each side frame rests upon and is secured to a pair of journal boxes 13, the latter receiving the ends of a pair of wheel carrying axles 14. Supported in any suitable man-

ner by the central portion of each side frame is a series of springs 15 and supported thereby are the end portions of a relatively light bolster 16. This bolster is preferably cast and formed at its center is a pocket 17 which receives a spring 18. This spring is of sufficient size and tension as to carry a portion of the weight of the supported car body and bearing directly upon the upper end of said spring is a part of the car underframe or a body bolster 19. A king pin 16^a upon which the bolster 16 is swiveled is seated in a part of the car underframe or body bolster and projects downwardly through the spring seated in pocket 17. Secured in any suitable manner to the end portions of this body bolster and on the underside thereof are bearing faces or brackets 20, in each of which is mounted for rotation a pair of tapered rollers 21 which rest directly on top of the end portion of bolster 16.

In Figure 5 I have shown a type of plano-convex roller wherein the roller body is provided with a single flat face or surface 21^a and which latter is adapted to normally rest directly on top of the flat upper face of the end portion of the bolster. By virtue of this construction, the truck will be held normally rigid while traversing straight portions of the track, and a considerable horizontal force will be required to act upon the rollers to cause them to perform their rolling functions and permit the truck to swing in a horizontal plane relative to the car body and which action occurs when the truck is passing around a curved portion of the track.

The degree of force required to move the rollers from their normal positions is in proportion to the extent or area of the flat surface 21^a and its ratio to the diameter of the roller. This ratio between the flat surface and the diameter of the roller is regulated by the factor of adhesion, or coefficient of friction, between the roller and its support or between the roller and the bearing between it and the interposed weight. This ratio must not be greater than the factor of adhesion, and preferably should be somewhat less so as to insure a rolling instead of a sliding movement of the roller when the force is applied.

It will be understood that the coefficient of friction or factor of adhesion between two similar materials is equal to the tangent

of the angle of repose, and that in the present construction the angle of repose is the outside angle A (Figure 7) formed by half the flat portion of the roller and a line connecting one end of the flat portion with the intersecting point between a vertical center line on the roller and the arc of the circle or circumference of the roller. This angle of repose is equal to angle B and which latter is enclosed by a line drawn vertically through the center of the roller and a line drawn from the center of the bearing at the top of said roller to the edge of the straight flat portion 21°. As these angles are alike, their tangents are the same and in order to be assured that the resistance to rolling movement is less than the factor of adhesion between the roller and the bearing, it is only necessary to have the tangent of angle B less than the factor of adhesion and the latter being known, the former can be readily established.

In Figure 8 a modified form of double plano-convex roller is shown wherein flat bearing faces are formed at the top and bottom of the roller and in this instance the angle is measured by the lines as shown, one of these lines extending vertically from the extreme end of the top bearing surface to the extreme opposite end of bottom bearing surface, and a line drawn between corresponding edges of both bearing surfaces.

The tangent of the enclosed angle B in Figure 8 is taken as the ratio to be observed, and for practical purposes it should not be greater than the coefficient of friction between the roller and its bearing.

My improved construction provides a truck which supports practically all the weight of the car and its contents directly over the side frames and journals of the truck. A portion of the weight of the car is borne by the springs 18 interposed between the truck and body bolsters. This weight is transmitted through the bolster springs 15 and side frames of the journal boxes, from thence to the wheel carrying axles so that at all times this portion of the weight of the car will be distributed equally between the ends of the axles.

The purpose of spring 18 between the light truck bolster and the body bolster of the car at or near the centers of said bolsters is substantially the same as that described in the Pfleger Patent No. 1,147,430, dated July 20, 1915, i. e., when one or both wheels of the truck at one side pass over or rest in a depression of the track, the main supporting springs under the ends of the body bolster on that side will tend to become exhausted, and as these springs distend, the spring 18 exerts its energy in assisting to support the weight of the car at its center.

65 The above condition presupposes a rigid

underframe in which the corner of the car above the wheels lying in a depression of the track is otherwise unsupported, assuming, of course, that the car is evenly loaded. If the car underframe is made of wood, or is 70 pliable to the extent that the corner over the wheel or wheels lying in a depression in the track rests upon the side bearings, then, of course, the spring 18 might not be brought into action, or, if brought into action, not to the extent that it would expand if the corner of a rigid framed car overhanging the wheels in the depression and there was a separation between the car underframe and the depressed truck side frame. 75

In rounding curves, the truck bolster side frames, and wheel carrying axles will rotate about the center of the bolster or about the king pin 16°, and under such conditions, the rollers 21 will perform the functions of rolling bearings to permit the relative movement between the truck and body bolsters, and said rollers are tapered inwardly so as to permit free rolling movement in curved paths on top of the ends of the truck 90 bolster.

It will be readily understood that minor changes in the size, form and construction of the various parts of my improved car truck can be made and substituted for those 95 herein shown and described, without departing from the spirit of my invention, the scope of which is set forth in the appended claims.

I claim:

1. In a car truck, a bolster pivoted to a part of the car body so as to swing in a horizontal plane, a pair of side frames, springs interposed between said side frames and bolster, and a spring interposed between the 105 central portion of said bolster and a part of the car body.

2. In a car truck, the combination of a bolster pivotally connected to a part of the car body so as to swing in a horizontal plane, 110 a pair of side frames, springs interposed between said side frames and the bolster, and plano-convex roller bearings arranged between the bolster and parts of the car body.

3. In a car truck, the combination of a 115 bolster pivotally connected to a part of the car body so as to swing in a horizontal plane, a pair of side frames, springs interposed between said side frames and the ends of the bolster, and plano-convex bearings carried 120 by the car body and disposed above the ends of the bolster and the spring supporting the same, the flat surfaces of said bearings engaging the bolster.

4. In a car truck, the combination of a bolster pivotally connected to a part of the car body so as to swing in a horizontal plane, a pair of side frames, springs interposed between said side frames and the bolster, roller bearings carried by the car body and dis- 125

130

posed above the ends of the bolster and the springs supporting the same, said roller bearings being provided with flat bolster engaging faces and a spring interposed between 5 the central portion of the bolster and a part of the car body.

5. In a car truck, a pair of side frames, a bolster yieldingly supported thereupon, which bolster is pivoted to swing in a horizontal plane, a spring interposed between the central portion of said bolster and a part of the car body, and a roller arranged between the ends of the bolster and a part of the car body, a portion of the periphery of 15 said roller being flat.

6. In a car truck, a pair of side frames, a bolster yieldingly supported thereupon, which bolster is pivoted to swing in a horizontal plane, a spring interposed between the 20 bolster and a part of the car body, and rolling supports arranged between the ends of the bolster and a part of the car body, which rolling supports are provided with flat bearing surfaces.

25 7. The combination with a body bolster provided on its underside with bearing rollers, portions of the peripheries of which are flat, of a truck bolster pivotally connected to said body bolster, the ends of which truck 30 bolster normally engage against the flat surfaces of said bearing rollers, a spring interposed between the body and truck bolsters, and side frames yieldingly arranged beneath the ends of the truck bolster.

35 8. The combination with a body bolster provided on its underside with bearing rollers, portions of the peripheries of which are flat, of a truck bolster pivotally connected to said body bolster, the ends of which truck 40 bolster normally engage against the flat surfaces of said bearing rollers, a spring interposed between the central portions of said body and truck bolsters, side frames positioned beneath the end portions of the truck 45 bolster, and springs interposed between said side frames and truck bolster.

9. In a car truck, a bolster pivotally mounted near its center so as to swing in a horizontal plane, a pair of side frames, springs 50 interposed between said side frames and said bolster, and plano-convex bearings arranged between the bolster and a part of the car

body for normally mounting the bolster in position at right angles to the center line of the car body and retaining said side frames 55 in planes parallel to the track rails.

10. In a car truck, the combination with a truck bolster adapted to be pivoted near its center to the car so as to swing in a horizontal plane, and plano-convex bearing rollers 60 interposed between said bolster and the car body, the flat bearing surfaces of said rollers being tangential to an angle between the vertical center line through each roller and a line drawn from the center of the opposite 65 bearing point of said roller to the edge of the flat surface, whereby the factor of adhesion between the roller and its bearing is less than its rolling tendency.

11. In a car truck, the combination with a 70 bolster designed to be pivoted near its center so as to swing in a horizontal plane, the plano-convex bearing rollers co-operating with said bolster, the flattened portions of said bearings having rolling resistance less 75 than the factor of adhesion between said bearing surfaces and said bolster.

12. In a car truck, the combination with a spring supported truck bolster that is pivoted near its center for horizontal swinging 80 movement, of plano-convex rollers disposed above the end portions of said bolster, the flat portions of each of which rollers providing a flat bolster engaging surface.

13. In a car truck, the combination with a 85 spring supported truck bolster that is pivoted near its center for horizontal swinging movement, of plano-convex tapered rollers disposed above the end portions of said bolster, the flat portion of each of which rollers 90 providing substantially flat bolster engaging surface.

14. In a car truck, the combination with a body bolster, of a spring supported truck bolster arranged beneath and pivoted to said 95 body bolster so as to swing in a horizontal plane, and plano-convex bearing rollers arranged between said bolsters, the flattened portions of the peripheries of said bearing rollers providing bolster engaging faces. 100

In testimony whereof I hereunto affix my signature this 16th day of July, 1919.

CHARLES T. WESTLAKE.
